Inventor:

August C. Dobrick,

by John Howard McElroy his Atty.

UNITED STATES PATENT OFFICE.

AUGUST C. DOBRICK, OF CHICAGO, ILLINOIS, ASSIGNOR TO THE IMPERIAL BRASS MANUFACTURING COMPANY, OF CHICAGO, ILLINOIS, A CORPORATION OF ILLINOIS.

COVER FOR PRIMING-CUPS.

1,372,220.

Specification of Letters Patent.

Patented Mar. 22, 1921.

Application filed April 15, 1920. Serial No. 374,004.

To all whom it may concern:

Be it known that I, AUGUST C. DOBRICK, a citizen of the United States, and a resident of Chicago, in the county of Cook, and State 5 of Illinois, have invented certain new and useful Improvements in Covers for Priming-Cups, of which the following is a full, clear, and exact specification.

My invention is concerned with priming 10 cups for engine cylinders, etc., and is designed to furnish such devices with a simple and inexpensive cover that is automatically opened or closed as the valve associated with the cup is turned to open it or close it, 15 and which can be readily attached to such cups, if desired.

To this end, it consists of a novel construction to illustrate which I have attached hereto a sheet of drawings in which the 20 same reference characters are used to designate identical parts in all the figures of which—

Figure 1 is a side elevation of a valve employing my invention;

25 Fig. 2 is an end elevation of the same;

Fig. 3 is a view similar to Fig. 2 but showing the valve partly opened; and

Fig. 4 is a perspective view of the cover detached.

30 I have shown my invention as applied to a priming cup of an ordinary construction in which the cup *a* is formed on the upper end of the body *b* of the valve, which has the tubular extension *c* with the lower end 35 threaded so that it can be screwed in place. A passage *d*, indicated in dotted lines in Fig. 1, extends from the cup through the body and extension. The body *b* contains a conical valve seat, indicated in dotted lines 40 at *e*, and coöperating therewith is the conical valve *f*, which preferably has the handle *g* formed integral therewith. An aperture *h* through the valve *f* preferably stands in the 45 closed position when the handle *g* is vertical, as seen in Fig. 1. The reduced end *j* of the valve is provided with an aperture through which is passed the cotter pin *k* coöperating with the washer *l* which engages the helically coiled expanding spring *m* the 50 other end of which engages a washer or disk which engages the side of the body member *b*. The foregoing is a customary and well known construction.

In carrying out my invention, I employ a

detachable cover seen in perspective in Fig. 55 4, and which is preferably formed up from sheet metal, and has the circular cover portion proper *n* which is slightly concave, as shown, with its concavity a portion of a sphere with the point of intersection of the 60 passages *d* and *h*, as a center. An extension *o* projects downward from the cover *n*, and an offset portion *p* connects it with the portion *q*, which has the function of the customary washer adjacent the valve body. It 65 has a perforation *r*, which corresponds in shape to the cross-section of the extension *j*, which may be any desired shape, except circular, and which is preferably a circle with two sides flattened. This construction 70 compels the cover to turn with the handle.

I preferably round off the upper edges of the cup, as seen at *s*, and the concave under side of the cover is so designed that it barely clears the curved edge *s*, so that when the 75 valve is closed, as seen in Figs. 1 and 2, the cup is covered and thoroughly protected from the dust, or rather dirt, that might tend to get into it and to be washed down into the cylinder with the next priming 80 charge. So long as the valve is closed, the cup is covered, and as soon as the valve is turned to open it it is uncovered, so that a single motion or movement of the valve is all that is necessary to prime it. 85

It will be noted with this construction that the valve can be opened by turning the handle *g* in either direction, which is frequently a matter of much convenience in locking them in contracted spaces. 90

While I have shown and described my invention as embodied in the form which I consider best adapted to carry out its purposes it will be understood it is capable of modifications, and that I do not desire to be 95 limited in the interpretation of the following claims, except as may be necessitated by the state of the prior art.

What I claim as new, and desire to secure by Letters Patent of the United States is: 100

1. In a device of the class described, the combination with a body having a valve seat therein, a passage therethrough, and a cup thereon with its top edge located in a single plain surface generally at right 105 angles to the passage therethrough, of a valve member rotatable in the valve seat, and a cover supported from the valve mem-

ber by an arm and having its spherically concave under surface adapted to swing closely over the top of the cup from either side thereof.

- 5 2. In a device of the class described, the combination with a body having a conical valve seat therein, a passage therethrough, and a cup thereon with its top edge located in a single plain surface and extending generally at right angles to the passage therethrough, of a conical valve member rotatable in the valve seat a helical spring on the small end of the valve member, a washer coöperating with one end of the spring, and
10 15 a cover supported from the valve member by an arm and having its spherically concave under surface adapted to swing closely over the top of the cup from either side thereof, the lower end of the arm coöperating with the other end of the spring, and means for securing the spring washer and arm in place on said small end.
20 25 3. In a device of the class described, the combination with a body having a conical valve seat therein, a passage therethrough, and a cup thereon with its top edge located in a single plain surface and extending generally at right angles to the passage therethrough, of a conical valve member rotatable in the valve seat and having its
30 smaller end non-circular in cross-section, a helical spring on the small end of the valve

member, a washer coöperating with one end of the spring, a cover supported from the valve member by an arm having an aperture in its lower end of the same cross-section as the small end of the valve member upon which it fits, said cover having a spherically concave under surface adapted to swing closely over the top of the cup from either side thereof, and means for securing the spring washer and arm in place on said small end.

4. As a new and useful article of manufacture, a cover consisting of a spherically concave disk having an arm extending downwardly therefrom and provided at its lower end with a non-circular aperture, for the purpose described.

5. As a new and useful article of manufacture, a sheet metal cover consisting of a spherically concave disk having an arm extending downwardly therefrom composed of two parallel portions connected by an offset, the lower portion having a non-circular aperture therein, for the purpose described.

In witness whereof, I have hereunto set my hand and affixed my seal this seventh day of April, A. D. 1920.

AUGUST C. DOBRICK. [L. S.]

Witness:

JOHN HOWARD McELROY.
